UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

PORTABLE SCOVING.

Application filed April 21, 1924. Serial No. 707,856.

To all whom it may concern:

Be it known that I, CLAUD E. FULLER, a citizen of the United States, and a resident of New York, in the county and State 5 of New York, have invented an Improvement in Portable Scoveling, of which the following description, in connection with the accompanying drawings, is a specification, like reference characters on the drawings 10 representing like parts.

My present invention relates to scoveling, and more particularly to an improved form of portable scoveling for brick kilns and the like.

15 As is well known, in a brick kiln it is necessary to protect the sides of the kiln by a scoveling which may be either built onto the sides of the kiln or a portable scoveling used, the idea being to economize fuel and 20 obtain a more even heat during the burning process. What may be called permanent scoveling is expensive to manufacture and results in a great many ruined brick because of the material of the scoveling adhering to the same during the burning process. Portable scoveling as at present utilized 25 is also unsatisfactory because of the difficulties of handling the same and the liability to breakage and warping because of 30 the intense heat to which it is subjected and no satisfactory means has heretofore been devised for obviating the results of cracking or warping. Further, in portable scoveling as at present utilized, there is no 35 satisfactory way of inserting therein the usual and commercial form of kiln door.

In my present invention I have obviated the objections to portable scoveling as heretofore made and have provided a novel form 40 of portable scoveling which may be easily and readily handled by the ordinary conveyor mechanism found in a brick kiln and in which any cracking due to expansion, contraction, or handling of the material can 45 be taken up. Further, in my new and improved form of scoveling the usual and commercial type of kiln doors may be built in and when so built in, form a part of the scoveling itself and may be handled with 50 such scoveling. Also, by my improved invention I am enabled to hold a section or sections of scoveling in an upright position while the kiln is being emptied and in a predetermined slope while the kiln is being 55 filled and thereafter releasing the scoveling

so that the weight of the scoveling will act to hold the brick in place and close up the space occasioned by the shrinking of the brick during the process of burning.

In carrying out my improved invention 60 I arrange channel irons at the top and bottom of the scoveling which is built up from insulating and fire resisting material and arrange a plurality of rods that run entirely through the insulating and fire re- 65 sisting material and such rods cooperate with the channel irons at the top and bottom of the sections of scoveling whereby the rods, when placed under tension, will take up any cracking caused by the expansion 70 and contraction of the material or the handling of the scoveling.

Heretofore where it has been attempted to utilize portable scoveling, it has been necessary to provide a long steel fork which 75 was attached to the crane and which fork was adapted to be inserted underneath the slab of scoveling when moving the same, and in order to keep the slab of scoveling lying properly in the forks it was necessary to 80 have it so hung that the slab was lying at an angle in the forks. This necessity for inclining the slab of scoveling rendered it impossible to accurately position the slab with respect to the kiln and also rendered neces- 85 sary a considerable amount of room between the stacks of bricks and the posts of the kiln building. I have obviated this objection in my present structure and have provided means secured to the top of the slab 90 of scoveling, such means being adapted for attachment to the crane hooks. I am enabled, by this improved structure, to manipulate the scoveling in the minimum amount of room which is of material advantage in 95 allowing the fullest use of the kiln building in building the kiln. By this method of handling the scoveling I am also enabled to fix the slope of the scoveling with respect to the yet unbuilt kiln, the slope given to 100 the scoveling governing the settling of the brick in the kiln, and after the kiln is built, I utilize means associated with the scoveling so that such scoveling will follow the brick during the process of burning the 105 same and prevent the openings which would otherwise occur.

The principal object of my invention, therefore, is an improved and novel form of portable scoveling for brick kilns and the like. 110

Another object of my invention is a portable scoving section having as an integral part thereof and inset therein the commercial type of kiln door.

5 A further object of my invention is an improved and novel means for taking up any cracking due to expansion and contraction or handling or warping of the scoving section.

10 In the accompanying drawings illustrating a preferred embodiment of my invention as located in a kiln,

15 Fig. 1 is a sectional elevation through a shed showing a kiln in elevation and with my improved scoving in position with respect to such kiln, and

20 Fig. 2 is a side elevation of Fig. 1 showing in front elevation a section of scoving having positioned as an integral part thereof the commercial type of kiln.

25 Referring to the drawings, the shed is constructed in the usual manner of a plurality of uprights 10 spaced apart from each other and tied together at their top by tie rods or beams 11, a roof 12 being built at the upper end of the uprights 10. At any convenient height above the ground level and attached to the uprights 10 are supports 13 on the upper end of which rest and are secured eye 30 beams 14 running parallel to the length of the shed as is usual. Secured to the top of the beams 14 are rails 15 arranged parallel to each other and constituting tracks on which run wheels 16 rotatably mounted on, 35 and supporting, the travelling crane beams 17. Means are provided, as indicated by the numeral 18, for causing a rotary movement of the wheels 16 and therefore a movement of the crane beams 17 along the length of the 40 building while a travelling carriage 19 is arranged with suitable means whereby an operator may control the crane mechanism. The above structure with regard to the crane is the usual structure and is well understood and a detailed description thereof appears to be unnecessary. Between the 45 ground level and the supporting beams 13 and secured to the uprights 10 are beams 20 provided at intervals with hooks 21 that extend inwardly toward the interior of the 50 shed for a purpose to be hereinafter described.

55 As is usual, the kiln is built up of a plurality of stacks of bricks 22 arranged in hacked relation in the usual manner, the kiln occupying the major portion of the floor space of the kiln, but leaving along each side wall, as defined by the posts 10, a passage for the workmen. In place of the usual 60 scoving I arrange sections of portable scoving, said sections being constructed by placing the channel iron 23 at the bottom and a channel iron 24 at the top arranged parallel to each other and of any suitable length. If 65 the section of scoving is not to be a section

through which the kiln may be fired, there is provided a slab 25 composed of insulating and fire resisting material and in the manufacture of such section of scoving it is desirable to employ a form of mold. Extending entirely through the slab or material 25 are rods 26 of any suitable or desired number, these rods being secured at their lower end to the channel iron 23 and their other end extends through perforations (not shown) 70 in the channel iron 24 and the extended ends of such rods 26 are threaded to receive nuts 27 and by means of which the channel irons 23 and 24 are forced firmly into engagement with the top and bottom ends of the slab 25. 75 As shown in Fig. 2, I have arranged three rods 26 in the slab 25, but the number may be varied as desired without departing from the spirit of the invention. Secured to the top channel member 25 are eyes 28 and the 80 number of such eyes may be any number desired, though I have found two to be ample. Secured to each of the eyes 28 is one end of a chain 29, which chain may be attached to the hooks 21 above referred to and which 85 chain, as will be seen from an inspection of Fig. 1, prevents a too far inward movement of the upper end of the section of scoving toward the kiln.

90 Where the section of scoving is to be located around the kiln at a point where it is desired to fire the kiln, kiln doors 30 are arranged on the lower channel iron 23 and the slab of material 25 is molded around the same, thus securely fastening them in 100 position.

95 In utilizing my improved sections of scoving the kiln is built in the usual manner and the crane operator, by manipulating the crane, hooks onto the eyes 28 and transports the sections of scoving to any 105 desired position around the kiln, as shown, for example, in the drawings, and, assuming it to be the ordinary section of scoving, it is placed with relation to the kiln with 110 the channel iron 23 closely adjacent to the bottom of the stack or unit 20 and inward movement of the upper end of the section of scoving is predetermined and limited by the use of the chain 29 in connection with 115 the hooks 21. The kiln is now built up in the usual manner of a plurality of stacks or units and, when the kiln is completely built, it is entirely surrounded by the sections of scoving. The chains 29 may now 120 be released from the hooks 21 so that the weight of the sections of scoving rests on the kiln and the tops of such sections of scoving will move inward toward the center of the kiln as the bricks forming the stacks or units 22 shrink during the burning operation. After the brick have been entirely burned, the tops of the sections of scoving may be moved toward the line of posts 125 10 and held thereagainst by means of the 130

chains 29 and hook 21 or may be moved to any portion of the shed desired by the use of the travelling crane.

While I have necessarily shown and described the preferred embodiment of my invention somewhat in detail, it is to be understood that I may vary the size, shape, and arrangement of parts within wide limits without departing from the spirit of the invention.

Having thus described my invention, what I claim as new is:

1. An improved portable scoving comprising a slab of insulating and fire resisting material of suitable thickness and means for placing the material of the slab under compression.

2. An improved portable scoving for brick kilns and the like comprising a slab of insulating and fire resisting material, a metallic member arranged at each end thereof, tie rods extending through the slab of material and metallic members, and means associated with said tie rods for forcing the metallic members toward each other whereby the slab of material between such metallic members is compressed and any cracks appearing in the slab from contraction and expansion or handling are taken

up.

3. An improved portable scoving comprising a slab of insulating and fire resist-

ing material, channel irons arranged at the top and bottom of such slab of material, a kiln door resting on the bottom channel iron and fitting into and through the slab of insulating or fire resisting material, a plurality of tie rods extending through the slab of material, and means for placing said rods under tension whereby the channel irons are forced toward each other to thereby compress the material of the slab to take up cracks in the material.

4. That improved method of utilizing portable scoving in connection with the building of kilns and the burning of the brick therein which consists in setting the portable scoving at a predetermined slope to govern the setting of the brick in the kiln, securing such scoving in such predetermined position during the building of the kiln and then releasing the scoving whereby such scoving will follow the brick during the process of burning to prevent openings in the kiln.

5. An improved portable scoving comprising a slab of insulating and fire resisting material of suitable thickness, means for placing the material of the slab under compression, and operating rings secured to the top edge of such slab.

In testimony whereof, I have signed my name to this specification.

CLAUD E. FULLER.
